UNITED STATES PATENT OFFICE.

ROBERT W. SCOTT, OF BOSTON, MASSACHUSETTS, ASSIGNOR TO SCOTT & WILLIAMS, INCORPORATED, OF CAMDEN, NEW JERSEY, A CORPORATION OF NEW JERSEY.

RIB-KNITTING MACHINE.

1,083,564.

Specification of Letters Patent.

Patented Jan. 6, 1914.

Application filed May 7, 1913. Serial No. 766,092.

To all whom it may concern:

Be it known that I, ROBERT W. SCOTT, a citizen of the United States, and a resident of Boston, in the county of Suffolk and State of Massachusetts, have invented a certain new and useful Rib-Knitting Machine, of which the following is a specification.

The object of my invention is to improve the mode of operation of the instruments, which may be the instruments of the prior art, employed to knit rib webs, for the purpose of insuring the formation of the fabric under conditions imposing a greatly decreased strain upon the yarn composing the knit loops, my invention having special value in knitting webs of fine or coarse gage in which light and delicate yarns are employed.

My invention further relates to changes in the construction of rib knitting machines to enable them to practice my said method, especially of that class of machines employing in their operation a set of primary needles and a set of secondary needles for knitting the respective faces of the fabric.

In the accompanying drawings, Figure 1 is a vertical radial section through the cylinder and dial of a rib knitting machine of a usual type having therein my improved devices, on the line 1—1 of Fig. 2; Fig. 2 is an under plan of the dial cam cap of such a machine equipped with my new devices; Fig. 3 is a development of the cam cylinder showing the knitting cams; Fig. 4 is an enlarged section corresponding to Fig. 1 showing the relation of the needles and the yarn during the knitting of a stitch by the dial at one of the knitting points; Fig. 5 is a plan of a portion of the dial needles showing their relation to each other and illustrating the coaction of the needles and yarn; Fig. 6 is a view of the dial cam cap similar to Fig. 2 showing a modification; Fig. 7 is a view similar to Fig. 3 of the cam cylinder employed with said modification; Fig. 8 shows two kinds of needles employed in the needle cylinder in the form of the said modification.

The knitting of rib webs, essentially requiring the systematic drawing of loops of the new course at the edge of the fabric through previous loops in alternate wales, or groups of wales, respectively drawn to opposite faces of the fabric, may be as-

sumed for the purposes of this application to necessitate hooked instruments, conveniently latch needles, coöperating with each other to engage the new yarn and draw it through the old loop.

In cases where rib fabric is formed by the primary action of one set of needles, and the secondary action of the other set, difficulty is experienced in knocking the old loops carried by the secondary needles over the new loops of yarn which have just been introduced into the hooks of said needles. In all rib knitting machines with which I am familiar, the needles are actuated in a successive order with respect to their carriers, one set of either carrier, which may be termed primary needles, first drawing their stitches, the intervening yarn being laid over the needles of the other carrier, termed secondary needles, and the latter being then retracted to a point at which the hook of the needle is well within the edge of its carrier before the knocking over of the old loop, which knocking over is accomplished by the combined action of the take-up strain upon the fabric, and the reaction of the verge or edge of the carrier, or instruments at said verge, upon the said loop, tending to prevent it from following the moving needle.

But the moving secondary needle engages its new yarn in the middle of a run thereof extending between two adjacent primary loops, in which it is locked and by the distance between which the extent of said yarn is measured. The distance to which said run of yarn may be moved away from the line determined by the surface on which the primary needles operate is thus limited, and in order to move the secondary needles sufficiently far to cause the knocking over of its previous loop a dangerous strain is always more or less present in ribbed webs produced upon instruments so operated. In fine gage machines, in which the distance between two adjacent primary needles is often less than one sixteenth of an inch, this damage often amounts to a serious loss of tensile strength, and in webs of any gage, its influence upon the selection of yarns capable of being knit is well marked.

It is not practicable to operate the needles by any means at present known in the art to cause a simultaneous draft and knocking over at the two needle carriers, the lim-

iting factors in this respect having to do with interference of the needle latches of one set with the bodies of the needles of the other set, with the tendency of the closing latches to trap and shear-cut the yarn misplaced with respect to the hook of the needles and the latch by the movement of the needles of the other set, and with the strains created by the simultaneous reeving of the 10 entering yarn through a large number of moving needle-hooks.

In the operation of a prior art machine, for instance such a machine as an independent needle cylinder and dial machine of the 15 type shown, when my new devices are not employed, the needles of both the cylinder 2 and the dial 3 will be actuated to advance them with respect to the verge or edge of their respective carriers to clear their loops 20 behind their latches, to then engage the new yarn carried in a yarn guide 55, as is usual in their hooks (which said operations may be simultaneous), and then the needles of one of the carriers only will be withdrawn 25 into their carrier, to draw the new loop through the old loop, a similar operation upon the other carrier following within a short interval. The needles of the first carrier to knit are hereinafter referred to as 30 primary needles, and of the second carrier to knit as secondary needles.

Referring now to Fig. 5, the cylinder needles α having taken the yarn Y , for instance, will all be actuated at w to knit one face of 35 the fabric.

The needles α of the primary carrier having knit, the yarns extending between the knit loops of adjacent needles or groups of needles of said primary carrier will be engaged by the hooks of the advanced needles of said secondary carrier, and it will become necessary for the needles of the secondary carrier to so perform their operations as to draw the yarn so engaged into loops of 40 proper length for the secondary face of the fabric by a penetrating movement through the old loops engaged upon their shanks. The minimum movement possible for this purpose of pulling the new loop through 45 the old loop (which may be stated with the same meaning as knocking the old loop over the head of the needle on to the new loop) must be made with respect to the fixed line 50 of primary needles, and necessarily is of a dimension sufficient to place the yarn runs r now held in the hook of a secondary (dial) 55 needle and engaged at its ends with loops held on the cylinder needles under great strain. The farther the secondary needle is 60 compelled to move before its loop is knocked over, the greater becomes the strain. The mechanical conditions of the machine, requiring an open throat for the forming 65 fabric between the cylinder 2 and the dial 3 prevent the moving of the knocking-over

verge or edge v of the secondary carrier any farther toward the surface occupied by the primary needles.

I have described one way of overcoming the above difficulties in my application Serial No. 676,526, filed February 9, 1912, which discloses the device of separate instruments for the needles of the secondary carrier, to engage the old loops of that face of the fabric knit by said instruments, and 75 to positively move the said loops with respect to their needles, to secure knocking over with respect to runs of yarn, the strain on which has been relieved by the release of the primary needles from their stitch-drawing position. My present method and machine constitute another method for accomplishing the same ends, and improvements in the machine to practice said method. 80

With the employment so far as described of the old instruments I have devised a new order of performing the operations resulting in the decrease of the strain placed upon the yarn by the operation of the needles of the secondary carrier (as instanced the dial 3). This method comprises the steps of feeding the yarn to the primary needles, knitting with the primary needles, then releasing the yarn engaged by the primary needles, except so much 95 thereof as is necessary to pass around the thin metal of the hook of the needle; then drawing the yarn intervening between some of said primary needles only through the old loops hanging upon the secondary needles; 100 then relaxing the tension upon the secondary loops so drawn, thereafter completing the secondary knitting by drawing the remaining runs of yarn intervening between the primary needles through the old loops of the 105 other or secondary face. I have thus so ordered the movements of the instruments as to cause these operations to be successively performed with respect to yarns released and free for this purpose, each secondary 110 needle being given yarn from an adjacent needle not yet retracted and from the previously knit loop or loops near it, sufficient to enable it to make the long movement necessary for knocking over an old loop, 115 and the long loop formed by the said needle being in turn released, to be shortened by the long movement of an adjoining needle.

Referring now to Figs. 1 and 4, I have divided the secondary needles, shown as the 120 dial needles, into two intercalated sets which may comprise alternate needles or groups of needles y and y' having their butts at different distances from their hooks to enable independent actuation thereof. As shown 125 the longer needles y for the dial have their operating butts sufficiently inward of those of the short needles y' to enable their respective actuation by cam grooves 4 and 6 of the dial cam cap 5. Said dial cam cap 130

may, as usual, be built up of attached cam plates to provide such grooves 4 and 6 of proper conformation. Said grooves will successively present, in the direction in 5 which the needle butts travel with respect to the cam cap, advancing points 7, on the same radial line, to simultaneously open the latches of the dial needles with respect to the usual yarn feed and latch guard device 10 (not shown), which thereafter prevents said latches from closing until the needles are retracted for knitting. Said cam grooves will at a further point present maximum advancing points 8, for instance upon the 15 radial line C, Figs. 2 and 3.

Coöoperating with dial cams 8, the cylinder will present an advancing cam 9. Yarn may be fed at the plane C. The cylinder needles are immediately actuated to knit 20 with respect to the advanced dial needles, by the cylinder stitch cam 10, which may as usual be formed as a triangular body, vertically adjustable as by the usual screw and slot adjustment shown at 11 to vary the 25 length of the primary loop drawn by said cam 10 with respect to the dial needles y or any y', which now rest with their latches open and their heads beyond the line of cylinder needles, at the circumferential parts 30 of the cam grooves 4 and 6, shown at 12, 12, Fig. 2. The cylinder needles x having knit, they are immediately advanced by the cam 13 to the position shown in Fig. 4 to pay back or release the yarn drawn by their stitch 35 forming movement. The upper extent of the movement, which is not alone dependent upon the cam 13 for positively giving it, but may in part be caused by the strain put upon the yarn by movement of the dial needles, 40 although I prefer to positively give it by the cam 13, is limited by the guard cam 14, which may be vertically adjustable by means similar to the adjusting screw 11. Immediately upon the attainment of the position 45 shown in Fig. 4 by the needles x, I now actuate one set of the dial needles, shown as the needles y, to perform their knitting movement, and for this purpose provide an adjustable stitch cam 15, having its maximum 50 withdrawal point on the plane G of Figs. 2, 3, and 5. Coöoperating with the stitch cam, the cam groove 6 provides at the point 16 a circumferential portion taking the needles y' to a position in which their hooks are sub- 55 stantially in the plane occupied by the primary needles at this time, which is the position shown for the needle y' in Fig. 4 and at b in Fig. 5. The cylinder needles x and the dial needles y' have thus been brought into 60 a position at which the minimum possible extent of yarn will pass through the old loops and through the respective hooks, during the time of the stitch forming movement of the needle y, to which enough yarn 65 has been released by the advanced positions

of the needle y' and the needle x when in the position of Fig. 4 to enable the free recession of said needle y to draw the new dial loop through the old loop.

Immediately following the cam 15 in the 70 groove 4, I provide an advancing incline 17 coöoperating with the needles y to advance them to the position shown at c, c, in Fig. 5, that is to say, to a position at which their hooks are substantially in line with or in advance of the verge of their carrier, to release the strain upon the new yarn loop. During, or preferably following, this movement the needles y' may be retracted to knock over their loops, for instance by the 75 cam 18, which may be a pivoted and adjustable stitch cam of the form shown in Fig. 2.

Cam 18 is followed by a cam slope 19 to release the needles y' into line with the needles y now in the position e of Fig. 5. The 80 effect of these operations, as will be plain from Fig. 5, will be to permit the needles y in their successive positions a, c, e, to advance to release the yarn of their loops, to be used by the needles of the intercalated set y' in 85 the successive positions b, d, and f for drawing their new loops and knocking over their old loops, and finally to relieve the strain upon the loops taken by both the secondary needles y and y' during their passage of the 90 positions indicated at g and h, Fig. 5, which positions represent the conditions of the needles after they have been acted upon by the inclines 17 and 19 of their respective grooves 4 and 6. This position of the dial needles is 100 attained during the passage of the cylinder needles between the cams 13 and 14, said cylinder needles remaining at rest in the position shown in Fig. 4. It will be observed that the following steps have been 105 taken: First, the cylinder needles have knit, with respect to dial needles thrown out to engage the sinker wales between said cylinder needles, and said cylinder needles have then been released to a position at which they place the minimum possible tension upon the loops of the new yarn just knit; second, certain of the dial needles shown as alternate needles have then 110 performed their knitting movements during such time as the intervening needles of the dial have also been placed in a position to put no strain upon the new yarn held in their hooks; that is to say at the position b of Fig. 5, and thus to permit their yarn to be used by the needles y following them to draw elongated stitches sufficient to knock over their old loops; third, that the needles of the dial which had been in a position of rest to release their loops for this purpose 115 then operate during or after the release of the new loop by the following needles of the other dial series, also to permit the use of a part of the yarn employed in the knocking-over operation of the first series of secondary 120

needles to knit. Thus a dial stitch on a needle y is robbed or gives up some of its yarn to aid a needle y' to knit. The last needle of the secondary carrier to knit, as 5 described a short needle y' , will now be found to be holding loops n' slightly enlarged at the expense of the loops n of their flanking needles y , and larger than the loops o of the neighboring cylinder needles x ; 10 but, as will readily be apparent, the mean or average size of the dial loops and the cylinder loops will be only substantially one-half that necessary for the knocking-over operation under normal conditions, if the 15 adjustments are such as to cause a recession of the secondary needles into their carriers only sufficient to permit knocking-over, at the times of their maximum withdrawal illustrated at a and f in Fig. 5. By the described operations of withdrawing the 20 secondary needles into their carrier only sufficiently far to permit knocking over, at the time of their maximum withdrawal, and by the described operations of the secondary 25 needles in two sets, one of which knocks over in advance of the other, I have thus provided sufficient new yarn to be moved through the old loop, without having provided sufficient new yarn to permit these 30 operations to be performed simultaneously, or by successive drawing movements of adjacent secondary needles.

In order to now adjust the short loops which have been knit, I provide an adjustable retracting cam for the cylinder, shown 35 at 20, and adjustable retracting cams 21 and 22 for the needles y and y' of the dial. While I have shown the cam 20 in a position to precede in effect the operative position of 40 cams 21 and 22, it is obvious that these positions may be reversed. The effect of these cams is as indicated at Fig. 5, to adjust or distribute the yarn now completely interknit between the loops n , n' of the back or dial 45 face of the fabric and the loops o of the front or cylinder face thereof.

In the case of a multiple or double course machine such as that usually employed for wide fabrics, I prefer to reverse the order at 50 which the needles y and y' knock over their loops at the second feed or course; for instance, instead of the cam 15 having its stitch forming point in the groove 4 in advance of the stitch forming point of the cam 55 18 in the groove 6, I may provide at the next yarn feed in the groove 4 a knitting cam 150, to knock over the needles y at a later time than the needles y' , which will be operated by a cam 180 of the form and at the 60 position shown. The cylinder cam for the second feed or unit may, however, remain unaltered, comprising the cams 9, 10, 13, 14 and 20.

While I have shown the machine arranged 65 to knit one-and-one fabric, having regularly

alternating cylinder and dial needles, it will be understood that the formation of the secondary loops by the method pointed out may be effected with respect to two or more needles of the secondary carrier or dial having no primary or cylinder needle between them with similar advantages in reducing the size of the loop and especially in avoiding the strain impressed upon the yarn during the knocking-over operation. 70

In Figs. 6 and 7 I have shown one of the many variations of the arrangements of the machine which will suggest themselves to those skilled in the art. In this instance, the dial cam cap 51 is equipped with a single 80 groove 61 in which the cams 71, 81, 181, 221 and 182 may be dial cams of a familiar form, the cams 181 and 182 serving to actuate the single set of dial needles (which may be short needles y' such as those above described) to draw primary stitches at the planes M and R with respect to cylinder needles advanced by the advancing cams 91 of the cylinder, in which the cams provide two actuating grooves 25 and 26 in which 90 respectively stitch cams 101 and 102 coact with needles x' and x^2 such as are shown in Fig. 8. The cam 101 actuates the needles x' to draw their yarn during the occupation of a position of advance by the dial needles and the 95 neighboring cylinder needles x^2 while the cam 102 is positioned to actuate the needles x^2 during the occupation of a position of advance by the dial needles and the cylinder needles x' . The cylinder needles x' are advanced by a cam 131 to the position shown for the needle x in Fig. 4, before the actuation of the needle x^2 and the cam 102. The needles x^2 , after they have knit at the cam 102, are advanced by a cam 132 to the same 105 extent as the needles x' .

The loops of the primary and secondary faces are adjusted in the manner described in connection with Figs. 2, 3, and 5 by the operation of the draw-cams 201 in the respective cam grooves of the cylinder, which cams follow in point of time of action an adjustable draw-cam 222, Fig. 6, coöperating with the dial needles. It will be understood that a similar action takes place at the adjustable draw cams 202, in coöperation with the dial draw cam 221 at the next yarn feed. 110

As in the case above described in which the dial needles were the secondary set, I 120 may at a subsequent feed change the order in which cylinder needles, actuated as secondary needles in two sets, are respectively knocked over as, for instance, by providing the following cylinder cams 103, 104 in the respectively exchanged positions with respect to their needles and the cams 101 and 102 illustrated in Fig. 7.

My invention is readily applicable, it will be understood without specific illustration, as well to rib knitting characterized by the 130

formation on one or both faces of persistently tucked loops, for instance in connection with the making of cardigan or half-cardigan fabrics, as to the regular rib knitting shown and described as one illustrative instance. Machines for the said purposes may, as usual, be provided at alternate feeds or groups of feeds in both, or in one of the carriers only, respectively for said cardigan and half-cardigan knitting, with stitch cams having any usual structure for tucking at that feed. The usual constructions for this purpose may comprise advancing cams insufficiently high to clear the needles, or stitch-cams of insufficient loop-drawing extent to knock over the loops. When such cams are in use, the described knocking-over operation will be delayed to another or later course, with an accumulation of loops at the needles concerned, but when said knocking-over does take place, it will be with respect to neighboring needles advanced to a loop-relieving position in the manner I have fully described.

It will be apparent that, while I have described my method in connection with a circular rib knitting machine, the same movements of the needles with respect to their carriers and each other may well take place in rib knitting machines of the straight or flat bed type, and that the knitting instruments might be spring needles, capable of drawing the yarn with respect to a knocking-over verge or edge, as well as latch needles, and that the practice of my method in these cases would produce the same improved results.

What I claim is:—

1. A rib knitting machine including two sets of needles and their carriers, means for guiding a yarn to the needles, means to cause one of said sets of needles to draw said yarn through previous loops to knit a course of one face of a ribbed fabric; means acting thereafter to cause the needles of the other set to become operative in two series, the first series drawing the yarn intervening between the wales of the first set of needles through the old loops and relaxing said loops prior to the operation of the second series in a similar manner.

2. A rib knitting machine comprising needle carriers, independent needles therein, a guide for knitting yarn, and means to actuate the needles of both said carriers comprising a primary cam carrier and cams thereon to cause the first or primary set of needles to knit with said yarn, and means acting thereafter to cause the needles of the secondary carrier to knit with said yarn in two intercalated series; said means comprising cams to advance the needles of the series first to knit prior to the retracting movement of the series last to knit.

3. A rib knitting machine comprising

needle carriers, independent needles therein and means to actuate said needles comprising a primary cam carrier and cams thereon for advancing the needles of the primary carrier to take yarn, a yarn guide, coacting means to advance the needles of the other carrier to take said yarn, means to cause the first or primary set of needles to knit, and means acting thereafter to cause the needles of the secondary carrier to knit in two intercalated series, said means comprising cams to advance the needle of the series first to knit prior to the retracting movement of a neighboring needle of the series last to knit, and means acting upon the needles of each of said sets to cause them to adjust the length of the loops last knit.

4. In a rib knitting machine, primary needles and a carrier therefor, secondary needles and a carrier therefor, means to cause said primary needles first to knit with a common yarn taken by both sets of needles, means to cause needles of the secondary set intercalated among other needles of said set to knit and advance with respect to said primary needles to relieve the strain upon the yarn last taken; and means to cause the intervening needles of said secondary set to recede into their carrier to knit during the maintenance of the advanced position of the remaining needles of said secondary set.

5. A rib knitting machine comprising two sets of needles and their carriers, means for guiding a yarn to the needles, means coacting with needles of one of said sets to draw said yarn through previous loops to knit one face of a ribbed fabric; and thereafter to relax the tension upon said last knit loops; means coacting with certain needles of a second set to thereafter operate them in succession to knit loops of said yarn in separated wales of the other face of the fabric; means to relax the tension upon said last knit loops, and means to actuate the remaining needles of the second set to knit the intervening between the said loops.

6. A rib knitting machine comprising two sets of needles and their carriers, means for guiding a yarn to the needles, means coacting with needles of one of said sets to draw said yarn through previous loops to knit one face of a ribbed fabric and thereafter to relax the tension upon the knit loops; means coacting with certain needles of the second set to thereafter operate them in succession to knit loops of said yarn in separated wales of the other face of the fabric; means to relax the tension upon said last knit loops, and means to actuate the remaining needles of the second set to knit the yarn intervening between the said loops, and means for thereafter coöperating with the needles of both sets to cause them to adjust the loops of the last knit course to substantially the same length.

7. In a rib knitting machine, a primary carrier, a secondary carrier, a series of independently movable needles in said primary carrier, two series of independently movable needles in said secondary carrier, primary and secondary cam carriers for said respective needle carriers, a cam structure in said primary carrier for causing the primary needles to take and knit the yarn, cams in 10 said secondary carrier for causing the needles of both series to take the yarn, a cam for the operation of one set of said secondary needles only to cause them to recede into their carrier to knit, the point of recession following that of the knitting cam for 15

the primary carrier; means to relax the tension upon the loops drawn by the needles at said point of recession, and a cam for coaction with the other series of needles of the secondary carrier to cause them to recede 20 into their carrier to knit, the point of recession following that of the first mentioned series of said secondary needles.

In testimony whereof, I have signed my name to this specification in the presence of 25 two subscribing witnesses.

ROBERT W. SCOTT.
